UNITED STATES PATENT OFFICE.

ALBERT V. SHULL, OF HELENA, ARKANSAS.

TWINE-HOLDER.

1,046,877.

Specification of Letters Patent. Patented Dec. 10, 1912.

Application filed June 3, 1911. Serial No. 631,165.

To all whom it may concern:

Be it known that I, ALBERT V. SHULL, a citizen of the United States, residing at Helena, in the county of Phillips and State 5 of Arkansas, have invented a new and useful Twine-Holder, of which the following is a specification.

This invention relates to twine holders, its object being to provide a simple and durable 10 device of this character having means whereby, after the twine has been broken, the loose end thereof will be elevated away from the counter and to a point where it can be conveniently grasped.

15 A further object is to provide a device of this type having means combined therewith for supporting paper sacks or a roll of paper as preferred.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed can be made within the scope of what is claimed without departing from the spirit of the invention.

In the accompanying drawings the preferred form of the invention has been shown. 30

In said drawings:—Fig. 1 is a front elevation of the holder. Fig. 2 is a central longitudinal section therethrough. Fig. 3 is a front elevation of another form of holder. 35 Fig. 4 is a side elevation of that portion of the holder for supporting a roll of paper. Fig. 5 is a section through a cup which may be used for holding a ball of twine.

Referring to the figures by characters of 40 reference 1 designates an elongated frame which may be formed with apertures 2 for the reception of supporting means, not shown, and this frame has a front stop bar or rod 3, mounted therein, and another or 45 rear stop rod 4 also connected thereto. A pivot rod 5 extends transversely of the frame below the rods 3 and 4 and has an elongated bail 6 pivotally mounted thereon and carrying a guide spool 7. This bail extends between the rods 3 and 4 and is limited in its 50 swinging movement by them.

A spool 8 is mounted upon the rod 5 between the ends of the bail 6 and directly over a guide eye 9 formed at the center of a rod 10 secured in the frame 1.

Eyes 11 project downwardly from the frame and support hooks 12 extending from the upper edge of a board 13 on which spring clips 14 are mounted, these clips being adapted to engage and hold bags upon 60 the board. A guide eye 15 is arranged under the top of frame 1 at the center thereof and an arm 16 extends forward from the frame top and has a depending finger 17 provided with an eye 18.

The twine cone T is mounted in the usual manner on the bottom of frame 1 and the twine extends upwardly through eye 9, over spools 8 and 7 and thence through eyes 15 and 18 from which it hangs loosely.

It will be apparent that when the twine is pulled downwardly by the user, it will swing the bail 6 forwardly against the rod 3 and will then be pulled off of the cone T. After the twine has been broken and released the 75 spool 7 will swing back so as to cause the bail 6 to move against the rod 4. This movement of the spool will result in the elevation of the free end of the twine thus lifting it away from the counter, and to a point where 80 it can be conveniently grasped.

Should it be desired to use a ball of twine in connection with the device a cup 19 will be placed on the bottom of frame 1.

It will be apparent, by referring particularly to Fig. 2, that, when the structure is not in use but is to be stored away, the bail 6 can be swung into the frame 1 and against the cross rod 3, the device thus occupying 85 the minimum space.

Moreover in lieu of providing a bag holder such as has been described, a roll of paper, such as indicated at P, may be arranged below the frame 1, the eyes 11 receiving hooks 20 projecting upwardly from arms 21 having hooks 22 for receiving the trunnions 23 of the roll P. A spring plate 24 may be connected to arms 21 and bear on the roll P to facilitate tearing the paper.

What is claimed is:—

In a device of the class described, a frame, upstanding means on the bottom of the frame for engaging a body of wound twine, a cross rod secured within the frame above said means and having a central guide eye integral therewith and above the center of the supported body, a guide eye supported by and arranged under the top of the frame and directly over the first mentioned eye, means pivotally mounted at its lower end 110

within the frame and between said eyes, a
twine engaging spool at the upper end of
said means for gravitating against and hold-
ing taut that portion of the twine between
5 the eyes, said means being shiftable into and
adapted to be housed within the frame and
between the eyes, spaced means extending
across the frame for limiting the movement
of said pivoted means, and means extending
10 from the upper portion of the frame for sup-

porting the free end portion of the twine
beyond one side of the frame.

In testimony that I claim the foregoing as
my own, I have hereto affixed my signature
in the presence of two witnesses.

ALBERT V. SHULL.
